HENRY C. WILLIAMSON AND HERMAN PRIES, OF MICHIGAN CITY,
INDIANA.

DRAFT-RIGGING FOR RAILWAY-CARS.

SPECIFICATION forming part of Letters Patent No. 738,866, dated September 15, 1903.

Application filed March 27, 1903. Serial No. 149,902. (No model.)

To all whom it may concern:

Be it known that we, HENRY C. WILLIAMSON and HERMAN PRIES, citizens of the United States, and residents of Michigan City, county 5 of Laporte, and State of Indiana, have invented certain new and useful Improvements in Draft-Rigging for Railway-Cars, of which the following is a specification, and which are illustrated in the accompanying drawings, 10 forming a part thereof.

This invention relates to that type of draft-rigging in which the draw-bar is supported by a swinging chair.

The object of the invention is to provide 15 improved means for carrying the bar whereby the centering of it is rendered certain.

While it is important in car construction to provide for the lateral movement of the draw-bar to relieve it and other portions of the car 20 from strain and wear in rounding curves, it is also important that when the car is detached from others the draw-bar shall be in its central position in order to facilitate coupling.

The invention consists in the structure hereinafter described, and illustrated in the accompanying drawings, in which—

Figure 1 is a detail plan view of a draft-rigging as applied to a car, some portions being broken away. Fig. 2 is a detail transverse 30 vertical section on the line 2 2 of Fig. 1, and Fig. 3 is a detail transverse vertical section on the line 3 3 of Fig. 1.

There are shown in the drawings, of ordinary form, a pair of longitudinal car-sills 10 35 10, an end sill 11, a buffer-plate 12, a draw-bar 13, followers 14 15, and cheek-plates 16 17. A chair 18 supports the outer end of the draw-bar and is itself carried by two T-shaped links swinging from the buffer-plate 12. The 40 chair 18 is vertically apertured at each end, as shown at 19 19, and the head of the links 20 20 crosses the bottom of this aperture and receives its side walls upon each of their arms or hooks. The stem of each link projects upwardly through the aperture of the chair and enters a socket formed in the buffer-plate 12 and is secured therein by a pivot-pin 21, which is retained in place by means of a cotter-pin 22, passing transversely through a boss 23,

formed on the face of the buffer-plate, the 50 cotter-pin also passing through the pivot-pin 21. In this construction the bearing-points of the chair upon the links is outside of the vertical median line of the latter, and as the draw-bar is swung to either side the support 55 is upon the forward arm of each of the hooks. As a result the bearing-points swing upon shorter radii than if they were in vertical line with the center of oscillation, and consequently the path through which each bearing-point moves is more sharply inclined upwardly. This being the case, the draw-bar gravitates more readily to its central position than it would were its path more nearly horizontal, and any binding of the parts is more 60 certainly overcome. The draw-bar plays between curved shoulders 26 26 of a supporting-bracket 24 and similar shoulders 27 27 of a tie-plate 25, located above. The bracket 24 and plate 25 are preferably placed substantially midway between the normal position of the followers 14 15. The shoulders 26 27 form the center of oscillation of the bar. In order to give the draw-bar a central bearing upon the follower whatever may be its position, the 65 outer faces of the followers 14 15 are made 70 somewhat convex, as shown at 28 28.

The invention is applicable to various forms of draft-rigging, and any changes which might be required to apply it to forms other than 80 the one shown will be readily suggested by the skill of the mechanic.

While for the purpose of illustration a draft-rigging has been shown which is located between a pair of car-sills, the invention is 85 equally applicable to that form of construction in which special draft-timbers are employed.

We claim as our invention—

1. In a draft-rigging, in combination, a car-sill, a swinging draw-bar, a chair supporting the draw-bar and having vertical sockets through its ends, and double hooks having their stems passed through the sockets and pivotally attached to the sill. 90

2. In a draft-rigging, in combination, a swinging draw-bar chair, and supporting-links for the chair, the chair resting loosely 95

upon each link at two points one on each side of its center of oscillation.

3. In a draft-rigging, in combination, a swinging draw-bar, fixed guide-brackets therefor and having rounded faces.

4. In a draft-rigging, in combination, a swinging draw-bar, and a pair of followers each having its draw-bar-engaging face convex in form.

10 5. In a draft-rigging, in combination, a swinging draw-bar, a pair of followers each having its draw-bar-engaging face convex in

form, and a guide-bracket having rounded faces.

6. In a draft-rigging, in combination, a support, a swinging draw-bar, and a gravity-controlled centering-chair carried by the support and upon which the draw-bar rests.

HENRY C. WILLIAMSON.
HERMAN PRIES.
